RICHARD C. LEAKE, OF ROCHESTER, NEW YORK, ASSIGNOR TO GENERAL RAILWAY SIGNAL COMPANY, OF GATES, NEW YORK, A CORPORATION OF NEW YORK.

ELECTROMAGNETIC DEVICE.

1,299,965.

Specification of Letters Patent. Patented Apr. 8, 1919.

Application filed March 28, 1916. Serial No. 87,192.

To all whom it may concern:

Be it known that I, RICHARD C. LEAKE, a citizen of the United States, and a resident of the city of Rochester, in the county of Monroe and State of New York, have invented a new and useful Electromagnetic Device, of which the following is a specification.

This invention relates to electro-magnetic devices and more particularly to electro-magnetic devices known as rotary electric motor relays.

The primary object of this invention is to so construct a rotary electric motor relay that the circuit controlling contacts included therein may move gravitally or by applied force upon a deenergization of the motor of the relay independently of the armature of the motor.

Other objects and advantages will appear as the description of the invention progresses, and the novel features of the invention will be particularly pointed out in the appended claims.

In describing the invention in detail, reference is had to the accompanying drawings, wherein I have illustrated a preferred physical embodiment of my invention and wherein like characters of reference designate corresponding parts throughout the several views and in which:

Figure 1 is a vertical sectional view taken substantially along the vertical axis of the motor; Fig. 2 is a horizontal section of the motor taken on the line 2—2 of Fig. 1 looking in the direction of arrows *a*, including the windings of the motor; Fig. 3 is a detail plan view of the spiral cam shown in Fig. 1.

The relay consists generally of three parts, namely, a casing A, a circuit closing device B, and a motor C.

The casing A consists of a main body portion 1 having two separate end plates 3 which are fastened to the main body portion of the casing 1 in any convenient manner, as by screws.

Securely fastened to the top of the casing 1 is a plate of insulating material 6, having slots 7 cut in the under side thereof. A contact carrier 8 and a bearing arm 9 have their upper ends fitted in the slots 7 of the plate 6 and are fixed to said plate by means of bolts 10 and 11 respectively, which also constitute binding posts for at-

taching circuit wires. An oscillatory member 14 is pivotally supported between the lower ends of bearing arms 9, only one of which is shown in Fig. 1. The oscillatable member is made of insulating material, and fastened to its upper side by means of screw 15 is a contact finger 16, the outer end of which contacts with the contact in the lower end of the contact carrier 8 when the finger 16 is moved sufficiently upwardly. Attached to the bent up portion on the left hand end of contact finger 16 is a flexible connection 16' which electrically connects contact finger 16 to the binding post formed by bolt 11 of bearing arm 9. An arm 17 having a toothed sector 17¹ at its lower end, is fastened at its upper end to the under side of the oscillatable member 14 in any well known manner, as by screws 18.

The motor C consists of an iron shell 19, open at both the top and bottom, the top being fastened to the casing 1, in any well known manner as by screws. Within the shell 19 is an annular stator 20, made of laminations in the well known manner, and since the casing 19 is entirely open at the top, the stator 20 can be slid into its proper place in the case 19. The stator 20 is provided with the well known coils 21 and 22, the leads of which, as shown in Fig. 2, are designated by 23 and 24, and 25 and 26 respectively.

The rotor consists of a non-magnetic shell 27 of aluminum or other electrically conductive material, shown in Fig. 1, attached to a spider 28 which is pinned to a shaft 29 passing therethrough. The shaft 29 is journaled near its upper end in ball bearings 30 in the bottom of casing 1, and at its lower end in ball bearings 31 fixed in the supporting base 32, which just fits into the open space in the bottom of the motor casing 19. The base 32 has an upwardly projecting member 33 bearing upon its outer face, an annulus 34 laminated in the same manner as stator 20 and held in place by rivet pins 35. The annulus 34 forms a means for decreasing the reluctance of the magnetic path between diametrically opposite poles of the stator. A spiral cam 36 is keyed to the shaft 29 at its upper end and is adapted to engage the toothed sector 17¹.

Referring to Fig. 2, it will be seen that by closing switch 43 circuits will be formed as follows: one side of the secondary of the 110

transformer 37, wire 38, resistance 39, wire 40, lead 24 of the coil 21, coil 21, lead 23, wires 41 and 42, switch 43, and wire 44, back to the other side of the secondary of the 5 transformer 37; the other is from one side of the secondary of the transformer 37, wires 38 and 45, reactance 46, wire 47, lead 26 of coil 22, coil 22, lead 25, wires 48 and 42, switch 43 and wire 44, back to the other 10 side of the secondary of the transformer 37. Thus it will be apparent to those skilled in the art, that both coils on the stator 20 are energized but the phase relation of the currents therein will be different and a rotating 15 field will be established which tends to rotate the rotor 27.

Practical experiments have shown that if the horizontal medial plane of the rotor 27 is above the horizontal medial plane of the 20 stator 20, as shown in Fig. 1, then when current is applied to the stator 20, the rotor 27 and consequently the motor shaft 29 connected thereto will be moved upwardly. I attribute this action to the fact that the medial 25 plane or plane of the resultant magnetic field of the currents induced in the rotor, these induced currents being limited by the confines of the rotor, is displaced from the medial or resultant plane of the magnetic field of the stator, so that the reaction between these magnetic fields causes an endwise upward movement of the rotor. Obviously, the same principle may be used to cause a downward movement of the rotor, 30 or a movement horizontally or in any other direction, if desired. Applying this principle to the device shown in Fig. 1, it will be seen that spiral cam 36 will be moved up and into mesh with the teeth of the toothed sector 17¹, and as the motor rotates, the sector 17¹ will rock the member 14 on its bearing and bring the contact finger 16 into contact with the contact at the lower end of contact carrier 8. When energy is applied to the 45 motor C, by closing switch 43, shown in Fig. 2, the rotor 27 will move upwardly, as viewed in Fig. 1, and bring the cam 36, best shown in Fig. 3, into mesh with sector 17¹. At the same time rotor 27 will rotate in a clockwise 50 direction thus rotating cam 36 in a clockwise direction and as the cam 36 is in mesh with sector 17¹ consequently sector 17¹ will be moved upwardly.

It will be noted that the device shown and 55 described is of the single element nature so that when switch 43 is opened all the current will be cut off from the stator, and the rotor will drop back to its normal position carrying with it shaft 29 and the spiral cam 60 36, thereby disengaging the cam 36 and the sector 17¹ and permitting the oscillating member 14 to return to its normal position against a stop 37 mounted in the casing 1, without rotating the rotor 27. It is thus apparent 65 that after the sector 17¹ has been

shifted by the action of the motor, and current is cut off by opening switch 43 of Fig. 2, the oscillatable member 14, carrying the contact finger 16 will be unimpeded by gearing or by the rotor 27 in its return to its initial position and will be assisted in so doing by the weight of the sector 17¹.

Although I have particularly described the construction of one physical embodiment of my invention, and explained the operation and principle thereof; nevertheless, I desire to have it understood that the form selected is merely illustrative, but does not exhaust the possible physical embodiment of the idea of means underlying my invention. 20

What I claim as new and desire to secure by Letters Patent of the United States, is:

1. A relay for use in railway signaling, comprising a circuit controller biased to assume a predetermined position; a motor for operating said circuit controller comprising a stator and a rotor, said rotor being capable of movement endwise and being acted upon by a force tending to cause it to assume a position relative to said stator in which the medial plane of the magnetic field of the current induced in said rotor is displaced from the medial plane of the magnetic field of said stator, whereby the rotor is given a predetermined movement endwise when said stator is energized; and means operatively connecting said rotor with said circuit controller when said rotor takes said movement endwise. 95

2. A relay for use in railway signaling, 100 comprising a circuit controller biased to assume a predetermined position; an electromagnetic means for operating said circuit controller and including a movable element, said movable element being automatically given two different movements upon energization of said means, one for establishing operative connection to the circuit controller and the other for causing operation thereof, said element being biased in opposition to its connecting movement; and means including 105 said movable element for providing an operative connection between said circuit controller and said electromagnetic means, whereby the circuit controller is operated 110 when energy is applied to the electromagnetic means and may return to its predetermined position in response to its bias when such energy is cut off without being required 115 to drive the electromagnetic means backward. 120

3. A relay for use in railway signaling, 125 comprising a fixed contact and a co-operating movable contact, said movable contact being biased to assume a predetermined position; a stator having windings arranged to produce a rotating field when supplied with alternating current; a rotor disposed in co-operative relation with said stator and capable of axial movement, said rotor being 130

- biased by a force to assume a position in which the medial plane of the magnetic field of the current induced in the rotor is displaced from the medial plane of the magnetic field of the stator; and coöperating elements associated with said movable contact and said rotor and adapted to establish a driving connection between the rotor and the movable contact when the rotor is moved axially in opposition to its bias, said driving connection thus established by said coöperating elements being automatically interrupted when the rotor moves axially back to its biased position.
5. A relay for use in railway signaling, comprising a circuit controller biased to assume a predetermined position; electromagnetic means comprising a rotor acted upon by a force tending to move it axially in one direction, and a stator having a field winding arranged in coöperative relation with the rotor and acting when energized to cause axial movement of the rotor in the opposite direction; and gearing including coöperating parts carried by the rotor and said circuit controller and adapted to establish an operative connection between the rotor and the circuit controller when the rotor is moved axially by the energization of the stator, whereby said circuit controller will be operated to a circuit controlling position when energy is applied to the stator and may immediately return to its predetermined position in response to its bias without causing reverse rotation of the rotor when energy is cut off.
6. An appliance for railway signaling comprising a stator having a field winding arranged to produce a rotating field when supplied with alternating current; a shell type rotor arranged in coöperative relation with the stator and mounted to move axially, said rotor being biased to assume a predetermined position and being automatically moved in opposition to this bias when energy is supplied to the stator; and a movable element automatically connected and disconnected from said rotor as it is moved axially by the energization of the stator and by its bias, respectively.
7. A relay for use in railway signaling, comprising a circuit controller biased to assume a predetermined position; electromagnetic means for operating said circuit controller, comprising a stator and a rotor, said rotor being mounted on a vertical axis to move axially and being influenced by its own weight to assume a position relative to said stator in which the medial plane of the magnetic field of the current induced in said rotor is above the medial plane of the magnetic field of said stator, whereby the rotor is moved upon its axis as well as rotated when energy is applied to said stator; and means operatively connecting said rotor with said circuit controller when said rotor moves upward.
8. A relay for use in railway signaling, comprising a contact carrying member mounted for oscillation upon fixed pivots and biased to one extreme position, resilient contact fingers carried by said member, fixed contacts arranged to coöperate with said contact fingers in their extreme positions, electromagnetic means including a movable element for operating said member in opposition to its bias, and means including said element for automatically establishing and dis-establishing an operative connection between said contact carrying member and said electromagnetic means upon energization and deenergization thereof respectively, whereby the contact carrying member, after being operated, may return in response to its bias without being required to drive the electromagnetic means backward.
9. A relay for use in railway signaling, comprising a circuit controller biased to a predetermined position; electromagnetic means including a stator and a rotor for operating said circuit controller, said rotor being biased to move axially in one direction and being automatically moved in the opposite direction upon energization of the stator; and means acting upon the axial movement of the rotor in opposition to its bias for establishing an operative connection between the rotor and the circuit controller, whereby the circuit controller is operated when energy is supplied to the stator but may return in response to its bias when such energy is cut off without causing return movement of the rotor.
10. A relay for railway signaling comprising circuit controlling parts biased to one position, an alternating current motor for operating said circuit controlling parts and comprising a shell type rotor and a stator, said rotor being biased to move endwise in one direction and being influenced in the opposite direction in opposition to its bias when current is supplied to the stator, and means for utilizing the endwise movement of the rotor for automatically connecting and disconnecting the rotor and the circuit controlling parts of the relay.

RICHARD C. LEAKE.
